UNITED STATES PATENT OFFICE.

FREDERICK J. ROOT, OF CLEVELAND, OHIO.

PAPER BOX.

Application filed June 11, 1923. Serial No. 644,671.

To all whom it may concern:

Be it known that I, FREDERICK J. Root, a citizen of the United States, residing at Cleveland, in the county of Cuyahoga and State of Ohio, have invented certain new and useful Improvements in Paper Boxes, of which the following is a specification.

This invention relates to paper boxes, and has for its object to provide an improved box or container particularly adapted and intended for transporting ice cream.

The object of the invention is to provide an improved lock for the cover or end of the box. A further object is to provide an improved handle by means of which the box can be carried; and another object is to provide improved means for opening the box in such manner that the contents thereof can be sliced, the whole wall of the box being laid open by slitting the same by means of a string which also provides the handle.

The invention is illustrated in the accompanying drawings in which Fig. 1 is a side elevation of the box. Fig. 2 is a longitudinal section. Fig. 3 is an end view. Fig. 4 is a detail of one of the covers. Fig. 5 is a detail of the cylinder partly in section.

The body of the box or receptacle consists of a cylinder 6, preferably made of heavy paper or cardboard, of sufficient strength to hold its shape under ordinary conditions. Each end of this cylinder is fitted with a removable cover or closure consisting of a head 7 and a rim 8 seamed or otherwise joined thereto, the particular manner of constructing the cap being unimportant to the present invention. The rim of this cap or cover fits on the outside of the end of the cylinder. Each end of the cylinder 6 is slotted, as indicated at 9, for a short distance, and an endless cord 10 is caught in these slots, one part of the cord extending inside the cylinder and the other part outside, the latter part being slack to afford a handle.

The rim of each cover is provided with an angular or bayonet slit 11 entering from the edge of the rim, with a notch 12 at said edge, into which the string may be easily entered.

When the cover is placed on the cylinder, the string 10 is entered into the notch 12 and the slit 11, and the cover is then turned slightly, the string passing into the offset

part of the slit and thereby forming a lock which prevents the cover slipping off. The same arrangement may be provided at each end of the cylinder.

When the package is to be opened, the covers are manipulated to release the string from the slits 11, and the covers can then be pulled off. Then, by giving a sharp pull on the string 10, the paper body of cylinder 6 will be ripped or slit its whole length, and the string pulled out, permitting the cylinder to be opened out flat with a brick or block of cream resting thereon in convenient position to be cut up into slices.

It will be noticed that there is an entire absence of metal parts, the whole device being constructed of a paper tube, pressed paper caps, and a string. The parts are cheap, and can be readily assembled, and the container will be practically water-tight, it being noticed that the slits 9 are covered by the rims 8 when the covers or caps are in place.

The invention is not limited to the particular form shown, but modifications are possible within the scope of the following claims.

I claim:

1. A paper box comprising a cylindrical body and caps on the ends thereof, the ends of the body and the rims of the caps being slotted, and an endless string extending lengthwise within the body and thru said slits and forming a handle and adapted to be pulled to rip the wall of the box lengthwise.

2. A paper box comprising a cylindrical body, caps on the opposite ends thereof, the caps having inwardly projecting flanges fitting outside the ends of the body, said ends having open slits and said flanges having angular slits, and an endless cord extending lengthwise within said body and thru all of said slits, whereby the cord locks the caps on the body and may be pulled to rip the wall of the body lengthwise.

In testimony whereof, I affix my signature in presence of two witnesses.

FREDERICK J. ROOT.

Witnesses:

JOHN A. BOHMHARDT,
BESSIE F. POLLAK.
